UNITED STATES PATENT OFFICE.

ABRAM P. SHUPE, OF EAST CLEVELAND, OHIO.

TOWEL-HOLDING DEVICE.

1,404,240.

Specification of Letters Patent. Patented Jan. 24, 1922.

Application filed June 15, 1918. Serial No. 240,210.

To all whom it may concern:

Be it known that I, ABRAM P. SHUPE, a citizen of the United States, residing at East Cleveland, in the county of Cuyahoga and State of Ohio, have invented a certain new and useful Improvement in Towel-Holding Devices, of which the following is a full, clear, and exact description.

This invention relates to an apparatus particularly adapted for the holding of towels which are placed in a washroom or other public places, and affords a means for holding a stack of towels and locking the towels against removal from the device. An object of the invention is to provide a device which will hold a stack of towels which may be placed as a unit in a suitable supporting device and removed as a unit, at the same time providing a construction in which the towels are so mounted as to be convenient for use. Generally speaking, the invention may be said to comprise the elements and combinations thereof, set forth in the accompanying claims.

Reference should be had to the accompanying drawings which form a part of this specification, in which Fig. 1 shows in elevation, a device for holding and locking a stack of towels associated with a supporting means; Fig. 2 is a sectional elevation showing a stack of towels in position; Fig. 3 is a sectional elevation of a portion of a stack of towels and the device which holds them, illustrating the manner in which the towels are used; Fig. 4 is a fragmentary sectional elevation showing different positions of the towel-holding device in its support as the towels are used; Fig. 5 is an elevation of a portion of the towel-holding device; and Fig. 6 is an elevation showing a modified form of towel-holding device.

It is a very desirable and necessary thing that towels which are to be placed in washrooms or other places of more or less public nature where it is difficult or impossible to prevent the loss of towels due to appropriation of the same by users, that a suitable device be provided which will secure the towels in such a manner as to prevent their being appropriated by users, but, at the same time, such a device should be of such a nature as to permit the convenient usage of the towels. Furthermore, it is desirable from the commercial point of view, to provide a device in which stacks of towels may be conveniently handled with respect to removing

and replacing of the same by the persons charged with replacement of soiled towels by clean towels.

In the construction about to be described, it is the aim to produce a device fulfilling both of the conditions before mentioned.

Referring to the drawings, a suitable standard or support is indicated in Fig. 1, having side members 1 and 2, which side members are provided with suitable means for supporting the towel-holding device. In the present instance this is accomplished by providing the arm 2 with a hole 2^a, and the arm 1 with a slot 1^a which permits the towel-holding device to be removed.

The particular supporting standard, such as illustrated in the drawings, is not essential to the operation of the towel-holding device, and is merely illustrative of any proper means for the purpose.

Between the members 1 and 2 there is a support having an inclining face, such as indicated at 3, the purpose of which will be later referred to.

The towel-holding device itself, comprises a rod 4 and a rod 5, these rods being spaced apart and adapted to receive a stack of towels between the same for the purpose of holding the towels.

Adjacent to one of its ends, the rod 4 has an upright member 6 which is suitably secured to the rod, and upon the upright member 6 the rod 5 is pivotally supported. This may be conveniently accomplished by slotting the end of the rod 5 a sufficient amount to receive the upright member 6 and rounding off the corner of the upright member 6 so as to permit swinging movement of the rod 5.

At the opposite end of the rod 5, to that which has been under discussion, the rod 5 is slotted, and in the slot there is pivotally mounted a strap 7. This strap extends toward the rod 4 and is adapted to extend through a slot or the opening 4^a which is formed in the rod 4. The end of the strap 7 is provided with a plurality of openings 7^a and in one of these openings there is inserted a padlock or other locking device, such as indicated at 8, it being apparent that when the padlock or other locking device is inserted, the bars or rods 4 and 5 are locked with respect to each other.

Upon the rod 4 there may, if desired, be placed members 9 and 10, which members lie adjacent to the ends of the rod 4, and are

for the purpose of limiting any endwise movement of the rod 4 with respect to the brackets or members which support the rod so that there will be no interference between the uprights and the towel-holding device which would prevent the free swinging or turning movement of the towel-holding device as the towels are used.

In using the device, a stack of towels is placed between the rods 4 and 5, and the distance or space between the rods 4 and 5 is, of course, designed to be appropriate to receive a stack of towels of a given number. That is to say, if it be desired to hold a stack of fifty towels, the towel-holding device will be constructed so that the rods 4 and 5 are placed apart a proper distance to hold this number of towels, and so with any given number of towels, the space of the rods 4 and 5 is made appropriate for the stack of towels to be held.

The towels are placed between the rods 4 and 5 and the towels extend substantially upon both sides thereon of the rod. In other words, the towels are clamped at the middle portion thereof. When the towels are placed between the rods 4 and 5, the strap 7 is inserted through the slot 4^a and the padlock inserted in one of the openings 7^a. The pressure exerted upon the stack of towels by the rods 4 and 5 is sufficiently great to prevent the withdrawal or removal of the towels from between the rods 4 and 5.

In order to increase the hold that the bars 4 and 5 exert upon the stack of towels clamped between them, it may be desirable to provide the bars 4 and 5 with projections such as indicated at 4^b and 5^b, these projections being oppositely disposed and staggered with respect to each other. These projections merely increase the frictional hold of the bars 4 and 5 upon the stack of towels. Towels thus clamped may be so prepared at the place where they are laundered, and carried in these clamped stacks, to the places where they are to be used, and for the purpose of using the same, the clamping device with its towels is placed in a suitable support such as that shown in Fig. 1, in such fashion that the towels lie against the supporting member 3.

In using the towels, one of the towels on

the back of the stand, for instance, a towel as indicated at 12 is grasped and pulled over the rod 5 and when used is allowed to hang, still remaining over the rod 5. So in turn, subsequent towels are used and allowed to hang, and as the used towels accumulate, the weight of the towels will cause the rod 4 to turn in its mountings and when the ends of one portion of the towels are all pulled over the bar 5, the towel-holding device will be in such position as to permit the use of the other ends of the towels until both ends of all the towels have been used.

Having described my invention, I claim:

1. In a device of the character described, the combination with a pair of spaced upright supports having oppositely disposed journals; of a rod provided with trunnions at its ends which are freely mounted in the aforesaid journals, an upright member secured to said rod, a second rod pivotally secured upon said upright member and adapted to extend substantially parallel with the first mentioned rod, a strap pivoted to the second mentioned rod adjacent its end, said first mentioned rod being provided with an opening through which said strap is adapted to extend, and means for securing said strap against withdrawal from the said opening in the first mentioned rod.

2. In a device of the character described, the combination of oppositely disposed supporting members, an inclined towel support mounted between the said supporting members, a rod rotatably supported at its ends in the said supporting members, a second rod mounted upon the first rod, and adapted to hold a stack of towels clamped between said rods at substantially their central portion, means for holding the second rod in clamped relation against the towels, the said towels engaging and lying against the inclined towel support, the said first mentioned rod being adapted to turn in its bearings as the towels are used the space behind the supporting members being free from obstruction, whereby used towels may hang behind said towel support.

In testimony whereof I hereunto affix my signature.

ABRAM P. SHUPE.
